UNITED STATES PATENT OFFICE.

JOHN GREIVES, OF PATERSON, NEW JERSEY.

ELECTRICAL INSULATING MATERIAL.

SPECIFICATION forming part of Letters Patent No. 278,536, dated May 29, 1883.
Application filed February 15, 1883. (No specimens.)

To all whom it may concern:

Be it known that I, JOHN GREIVES, a citizen of the United States, residing in the city of Paterson, county of Passaic, and State of New Jersey, have invented certain new and useful Improvements in Electrical Insulating Material, fully described and represented in the following specification.

This invention consists in a composition containing two ingredients, chalk and colophony, (black resin,) combined in the manner and proportions herein specified.

In preparing my composition I take the commercial chalk and commercial rosin and reduce them to powder and mix them in suitable proportions.

For insulating conductors inclosed in a suitable casing, box, or covering, I can use the mixture in the form of powder, especially in cases where the composition is not exposed to dampness, which the chalk is liable to absorb, and thus injure the insulation; but in most cases I prefer to melt the rosin and mix the chalk thoroughly with it while in a heated state.

As the chalk is alkaline and the rosin consists of acid elements—as pluic, sylvic, and colopholic acid—a true chemical union takes place between the ingredients when heated, and a compound of essentially different properties from either ingredient results. Thus the chalk and rosin can both be readily cut with a knife, while the composition with a pre-powderance of the chalk appears like an artificial stone and resists wear and pressure very much better than either of the separate ingredients.

In like manner the tenacity of the compound is many times greater than that of either ingredient when chemically combined by heating the mixture.

The rosin having a very brittle nature, I find it preferable for most purposes to use an excess of the chalk, and employ from fifty to ninety per cent. of the latter, according to the hardness of the composition required. When the compound is to have a degree of flexibility I

employ from thirty to forty-five per cent. of the rosin, and add also about five per cent. of an oxidizing-oil. Such compound is pliable when cold and nearly as tough as sole-leather, so that it can be used for coating telegraph-wires, and resists flexure as well as a zinc or galvanized coating. I have not, however, claimed this subordinate or pliable mixture herein, but simply the composition of colophony and chalk prepared as described above, and containing from forty to ninety per cent. of the chalk. The resisting-power of this insulating material is such that a film one-sixteenth of an inch thick will resist a current of one-fifteen amperes per second.

Any novel subject-matter I have described and not claimed herein I have claimed in other patent applications or reserved to be claimed in future original applications, and having thus set forth the nature of my insulating composition, it will be seen that it differs from others previously patented in containing only the two ingredients, one of which is alkaline and the other acid, and that their chemical reaction is not affected or confused by the presence of other elements when united in the simple manner I employ. I therefore disclaim the use of chalk and rosin as heretofore used in compounds containing various other ingredients, my invention consisting in combining them in such a way that their natural affinity may be utilized and the expense of other ingredients is avoided.

Having thus described my invention, I claim the same as follows:

The composition for insulating electrical wires, consisting in chalk and colophony combined substantially in the manner and in the proportions specified.

In testimony whereof I have hereunto set my hand in the presence of two subscribing witnesses.

JOHN GREIVES.

Witnesses:

THOS. S. CRANE,
JOHN A. RODRIGO.

Correction in Letters Patent No. 278,536.

It is hereby certified that in Letters Patent No. 278,536, granted May 29, 1883, upon the application of John Greives, of Paterson, New Jersey, for an improvement in "Electrical Insulating Material," an error appears in lines 59 and 60 of the printed specification forming a part of said patent requiring correction as follows: the word "one-sixteenth" should read "one-sixtieth;" and that the specification should be read with this correction therein to make it conform with the record of the case in the Patent Office.

Signed, countersigned, and sealed this 26th day of June, A. D. 1883.

[SEAL.]

M. L. JOSLYN,
Acting Secretary of the Interior.

Countersigned:

E. M. MARBLE,
Commissioner of Patents.
